VENTILATED WALL CONSTRUCTION FOR ROLL-FORMER MACHINES AND THE LIKE

Charles F. Engel, Columbia, Ill., assignor to Engel Equipment, Inc., St. Louis, Mo., a corporation of Missouri

Filed Oct. 26, 1960, Ser. No. 65,135
5 Claims. (Cl. 153—10)

The present invention relates to the construction of machines having walls supporting a plurality of transverse rotating shafts, and it has particular application to the construction of machines having a succession of rolls in aligned upper and lower machine elements, for the progressive forming of sheet metal strips.

The purposes of the present invention include the following: to construct the walls of such machines from metal plates thin enough for punching and piercing operations, rather than the conventional cutting and boring operations; to cool and ventilate bushings for bearings supported by the walls and to provide better lubrication to such bearings; and to provide simple, reliable alignment and tensioning means between the walls of the upper and lower elements of such machines. Other purposes will be apparent from the remainder of this specification.

Such purposes are accomplished in the present invention, in general, by using walls each consisting of a pair of parallel, openly spaced plates, formed by punching and piercing, whose pierced bores support the ends of spacer members such as bushings whose midportions are diametrically enlarged to establish the spacing between said side walls, thus providing for the flow of ventilating air between the plates and the use of lubrication fittings at the midportions of the bushings. The spaces between the plates are also utilized to accommodate the alignment and tensioning members which connect and space upper and lower machinery elements relative to each other. The spacer bushings are diametrically enlarged on installation to secure the punched, pierced plates in flat parallel alignment.

A preferred embodiment of the present invention is shown in the accompanying drawing in which:

FIGURE 1 is a perspective view of the construction which is the subject of the present invention, as applied to one end of a progressive roll-former machine of the type having a series of pairs of mating rollers extending over a substantial length. Because of the general similarity of such progressive rolls in series, only the right end of the machine is illustrated.

FIGURE 2 is a view, partly in section, taken along line 2—2 of FIGURE 1, immediately beneath the outer side wall plates.

FIGURE 3 is a fragmentary sectional view taken along line 3—3 of FIGURE 1.

FIGURE 4 is a fragmentary sectional view taken along line 4—4 of FIGURE 1.

FIGURE 5 is a fragmentary sectional view taken along the left end of line 5—5 of FIGURE 1.

Referring to the drawing by the detail part numbers, I provide a work table surface 10, shown fragmentarily in FIGURE 1, having a rectangular cut-out 11. Screws 12 whose heads are flush with the table surface 10, engage threaded support blocks 13 set into and between outer and inner lower wall plates 14, 15 respectively of a lower machinery element generally designated *a*. The plate upper edges 16 project into the rectangular cut-out 11 and extend to the work table surface 10.

The wall plates 14, 15 are formed of rigid steel plate material thin enough to be blanked on a fairly high-capacity punch press or similar machine tool. These plates have a number of circular bores aligned with each

other, preferably formed by a mere piercing operation (nevertheless referred to as "bores"). The circular holes so pierced lie in two horizontal lines. In the upper line are the bushing bores 17, as shown in FIGURES 1 and 5; whereas the lower line consists of the smaller clamping bores 18, as shown in FIGURES 2 and 3. The bores 17 and 18 in the outer and inner plates 14, 15, are concentric with each other and, depending on the details of construction employed, may be of the same diameter or of different diameters.

The space between the outer and inner lower wall plates 14, 15, is established by several means. Typical and of principal importance are bushings 21, installed horizontally to join the bushing bores 17 of the outer and inner plates 14, 15. The preferred manner of installation is, forcing a hardened ball, whose diameter is slightly larger than that of the bushings 21 as supplied, through the center of the bushings 21 and thus expanding them to fit tightly within the bushing bores 17. The outer wall of each of the bushings 21 has end portions 22 which terminate inwardly in 90° shoulders 23. Between the shoulders 23 is a diametrically enlarged midportion 24 whose length equals the spacing to be established between the outer and inner wall plates 14, 15.

In FIGURE 5, the enlarged bushing midportion 24 is shown equipped with a radially drilled lubricating passage 25, at the outlet of which is a lubricating fitting 26, secured to a tube 27 for supplying lubricant under pressure, from a source not shown. While each of the bushings 21 may be so equipped for lubrication, if desired, in most installations such lubrication will be needed only for those bushings whose bearings receive the greatest load.

Spacing of the wall plates 14, 15 is also accomplished by spacing washers 30 such as shown in FIGURE 4, mounted on shoulder bolts 31 whose shank portions 32 fill the clamping bores 18. The shoulder bolts 31 engage tapped holes in the ends of rigid spacer rods 33 which extend transversely across the machine and establish the spacing of the inner wall plates 15 from each other. Conveniently, the spacer rods 33, with their attaching shoulder bolts 31 and spacing washers 30, are used in parallel horizontal rows, as shown in FIGURE 1, spaced between the successive forming rolls hereinafter described but vertically removed farther from the level at which the sheet metal to be formed will pass through the machine.

While the description so far has been directed specifically to the roll-carrying frame which forms part of the lower machinery element *a*, it applies as well to the upper machinery element, generally designated *b*, save in the respects hereinafter noted and which will be obvious from the drawings. Specifically, the upper machinery element *b* includes similarly spaced-apart outer upper wall plates 14' and inner upper wall plates 15' whose lower edges 36 are spaced a fraction of an inch above the level of the table surface 10. This spacing establishes a gap 37 at the right side of the machine through which a metal sheet, passed along the work table surface 10 generally outward of the right outer upper wall plate 15', may have its margin flanged by projecting it through the gap 37 and into the forming rolls closely thereadjacent. To permit such flanging action, the right U-bolt 40 shown in FIGURES 1 and 4, is spaced well inwardly of the forming roll portions adjacent to the inner wall plates 15, 15' at the right side of the machine. At the left side of the machine, the gap which would otherwise exist is blocked by the left U-bolt 41 and the alignment gibs 58, 59 hereinafter described.

With respect to bushing bores 17, clamping bores 18 and bushings 21, as well as the general arrangement of forming rolls, gears and other machinery elements hereinafter

to be described, the upper machinery element *b* is generally similar to the lower machinery element *a* and substantially symmetrical thereto about a horizontal plane taken through the middle of the gap 37.

Supported in the bushings 21 and extending on horizontal axes transversely across the lower machinery element *a* and the upper machinery element *b* are a succession of lower and upper progressive forming rolls generally designated 42, 42', 43, 43', 44, 44', etc., commencing at the right end of the machine as shown in FIGURE 1. The left end of the roll 43 is shown in FIGURE 5 and is typical. Beginning at its left end, it has a shaft end 45 formed with an outer cylindrical bearing surface 46 which is supported in a needle bearing 47 such as is featured in each of the bushings 21. Inwardly of the shaft end 45 is an integral gear 48, and to the right thereof is cut the lower roll profiles 49. It will be seen that the upper gears 48' and upper roll profiles 49' will mate with the corresponding power gears and roll profiles at each stage, from right to left. The roll profiles 49, 49' vary from right to left progressively to effect progressive forming of metal which is passed therethrough. Idler gears 50 and their needle bearings 50a are mounted on the lower frame spacer rods 33 (FIGURE 3) to mesh with the integral lower gears 48 (FIGURE 5) which are in mesh with the upper integral gears 48' (FIGURE 1). Thus, rotary power from a source not shown, is transmitted through the entire series of forming rolls.

The roll profiles 49, 49' have at least two different general patterns, the first of which provides for forming to the left side of the right U-bolt 40, and the other which provides for forming at the right side of the right U-bolt 40, in which case the metal to be formed may pass through the gap 37. The right U-bolt 40 in the position shown in FIGURE 1 has its counterpart in a second similar right U-bolt similarly mounted near the left end of the machine. Referring to FIGURE 4, the right U-bolt 40 has its lower bend 51 seated in a groove 52 in the lower spacer rod 33; and a correspondingly located but broader groove 53 in the spacer rod 33 directly above it serves as a seat for the lower semi-circular cut-out 55 of an inverted U-shaped saddle bracket 54. The parallel stems of the right U-bolt 40 extend through bores in the center of the inverted U-shaped saddle bracket 54 and through a somewhat resilient leather strip 56, against which adjusting nuts 57 bear to bring about the desired tightness of the assembly.

At the left side of the machine illustrated, precise planar alignment is maintained between the outer lower and upper wall plates 14, 14' and likewise between the inner lower and upper plates 15, 15'; also, fore-and-aft in-plane alignment is maintained. The parts which serve these functions will now be described.

On the shoulder bolts 31 which engage those spacer rods 33 onto which the left U-bolts 41 are to be mounted, lower and upper mating gibs 58, 58' serve as spacers between the inner and outer wall plates, 14, 14', 15, 15', as shown in FIGURE 3. As shown, the gibs 58, 58' consist each of two identical stamped-out pieces whose combined thickness equals the spacing washer 30. A single gib, cut from metal of the same total thickness, might have been used instead.

Each of the gibs 58, 58' has an outer pierced bore 59, of sufficient diameter to fit upon the shank portion 32 of a shoulder bolt 31; and has an inner bore 60 shown as being of somewhat larger diameter, which receives a heavy locating pin 61 extending through the corresponding locating pin bores 62 in the outer and inner lower and upper wall plates 14, 15, 14', 15', as shown in FIGURE 3. Half of the upper edge of the lower gib 58 is a tang 63, extending upward above the lower edge 36 of the upper wall plates 14', 15'. The other half is a cut-out 64 which extends downwardly below the upper edge 16 of the lower wall plates 14, 15. As shown in FIGURE 2, the upper gib 58' has in its lower edge a similar tang 63' and cut-out

64', the tang 63' extending below the upper edge 16 of the lower wall plates 14, 15, into the space provided by the cut-out 64 in the lower gib 58; while the cut-out 64' similarly accepts the tang 63 of the lower gib 58.

5 A second set of gibs is provided at some convenient point near the left end of the machine, aligned symmetrically with the set here described. Reciprocal movement of the tangs 63 within the cut-outs 64 permits vertical spacing of the upper machinery element *b* with respect to the lower machinery element *a*, for adjustment and resiliency of operation, but maintains fore and aft alignment; while the projection of the tangs 63 beyond the plate edges 16, 36 serves as a lateral aligning means.

10 Alignment is also preserved and adjustable tension applied, by the left U-bolt 41 whose U-shaped bend 65 fits around the rounded outer end 66 of the lower gib 58. The U-bolt 41 has parallel stems 67 spaced to fit closely about vertical side edges of the gibs 58, 58'. These stems 67 are longer than those of the right U-bolt 40 and extend 15 to and beyond the outermost edges of the opposite machinery element, that is, to and beyond the upper edges of the upper inner and outer wall plates 14', 15', and the diameter of the stems 67 substantially fills the space between the wall plates. A spanning bracket 68, of inverted 20 U-shape having sufficient inside width to span the spaced plates 14', 15', has bores through which the stems 67 pass. The upper surface of the inverted U-shape spanning bracket is equipped with a resilient leather strip 56, similarly bored, and adjusting nuts 57 bear thereagainst 25 to achieve necessary tension in the U-bolt 41, yet providing appropriate resiliency.

30 It will be seen that the open spacing of the vertical plates 14, 15, 14', 15', provides walls through which ventilating air will circulate freely, cooling the bushings 21. The oil originally supplied in the needle bearings 47 will therefore last much longer than without such ventilation. Wherever supplemental lubrication is provided to fittings 35 26 at midportions of the bushings 21, the wall plates between which the lubricant tubes 27 pass, protect them from inadvertent damage. Further, the simple alignment and tensioning connector means consisting of the U-bolts 41 and gibs 58, 58', utilize their snug fit within the spacing between the walls for a simplicity of construction and servicing.

35 It will be apparent that these objects of the present invention, so achieved by the embodiment illustrated, may also be achieved by varying the construction with known mechanical equivalents. Accordingly, the present invention is not to be construed narrowly, but as fully co-extensive with the claims which follow.

I claim:

1. For use on roll-former machines and the like, the construction comprising a plurality of transverse rotatable roller shafts, bushings supporting the shafts for rotation, and walls supporting and spacing said bushings, characterized in that the walls each comprise a pair of flat plates spaced from and parallel to each other and having aligned bores within which the bushings are secured at their ends, and in that the bushings each have a diametrically-enlarged midportion between its ends of such width as to space the plates from each other, whereby ventilating air may flow between said plates and past said bushing midportions.

2. The construction defined in claim 1, together with lubrication means communicating between the spaced plates to the mid portions of the bushings.

3. Roll-former machine construction of the type comprising an upper roll-carrying element and a lower roll-carrying element, each including a plurality of transverse rotatable roller shafts, bushings supporting the shafts for rotation, and vertical side walls supporting and spacing the bushings, the side walls of at least one side of said elements being in planar alignment with each other, characterized in that said side walls so in alignment each

comprise a pair of plates secured parallel to each other in open-spaced relationship, and in that connecting and aligning means are provided in the spaces between the plates of said side walls and extending from one element to the other.

4. Roll-former machine construction of the type comprising an upper roll-carrying element and a lower roll-carrying element, each including a plurality of transverse rotatable roller shafts, bushings supporting the shafts for rotation and side walls supporting and spacing the bushings, the side walls at at least one side of said upper element and said lower element being aligned with each other, each of said side walls so in alignment comprising a pair of plates, means to clamp the plates of each of said pairs parallel to each other in open-spaced relationship, and means located within the spaces between the said plates to maintain the said alignment.

5. Alignment and tensioning construction for machines of the type having aligned upper and lower machinery elements, comprising vertical walls for such elements, each wall having a pair of vertical wall plates, means securing them together in open-spaced, parallel relationship, an upper gib mounted between the walls of the upper machinery element, said gib having vertical side edges and having in its lower edge a tang portion extending downward below the upper edge of the wall plates of the lower machinery element and a cut-out extending upward above the lower edge of the plates of the upper

machinery element, a lower gib mounted between the walls of the lower machinery element, said lower gib being of the same width as the upper gib and having vertical side edges and having in its upper edge a tang portion extending upward above the lower edge of the wall plates of the upper machinery element and received within the cut-out of the upper gib, further having in its upper edge a cut-out extending downward below the upper edge of the plates of the lower machinery element, 5 within which cut-out the tang portion of the upper gib is received, further comprising a tension connector having a pair of parallel stems joined at one end and there mounted between one of said pairs of spaced wall plates, the stems extending vertically therefrom to and between the other pair of spaced wall plates and to the outermost edges thereof and encompassing between the stems the vertical side edges of the upper and lower gibs, together with a bracket spanning and bearing against said outermost edges of said other pair of spaced wall plates and 10 means mounted upon said bracket to exert tension on the stems of said connector.
